MONEY CHEST

Earl M. Knedler, 1434 Parnell Ave., San Antonio 24, Tex.

Filed May 21, 1962, Ser. No. 70,212

Term of patent 14 years

(Cl. D52—4)

Fig. 3

Fig. 4

Fig. 5

FIG. 1 is a perspective view of a money chest in open condition showing my new design;

FIG. 2 is a perspective view thereof in closed condition;

FIG. 3 is a rear elevational view;

FIG. 4 is a front elevational view; and

FIG. 5 is a side elevational view.

I claim:

The ornamental design for a money chest, substantially as shown.
